UNITED STATES PATENT OFFICE.

JOHN FREMONT FREY, OF INDIANAPOLIS, INDIANA.

METHOD OF PREPARING DRY MATS FOR STEREOTYPING.

1,093,323.

Specification of Letters Patent. Patented Apr. 14, 1914.

Application filed February 26, 1913. Serial No. 750,800.

To all whom it may concern:

Be it known that I, JOHN FREMONT FREY, a citizen of the United States, residing at Indianapolis, in the county of Marion and 5 State of Indiana, have invented a new and useful Method of Preparing Dry Mats for Stereotyping, of which the following is a specification.

My invention relates to the method of 10 preparing matrices for stereotype plates from dry flong mats, and has for its object the betterment of such matrices.

It has heretofore been considered that 15 clearer stereotype plates may be made from wet mats than from dry mats, because the dry mats as heretofore used were less plastic than the wet mats and in consequence would not so readily conform to the type face or give so great "depth" of impression, be- 20 sides causing injury to the type in molding. However, the use of wet mats requires a longer time, so that, especially in the rush of getting out a "rush" extra edition of a 25 newspaper, when every second counts, dry mats are much used although they have not heretofore given as good results as the wet mats. The delay in the use of the wet mats, and an unavoidable delay, is that due to the necessity for the drying of the wet mats on 30 the drying table, and perhaps for heating up the drying table as in the case of an unexpected extra, after the mat has received the type impression.

With my invention, dry mats are made 35 softer and more plastic, so that they take the type impression more readily and accurately and with greater depth, by conditioning them in a special form of humidor which I have devised. By this humidor the dry 40 mats are made humid uniformly, so that they better take the type impression, but they are not made wet and do not require drying on the drying table. After the properly conditioned dry mat has received 45 the type impression, it is only necessary to place it for a few seconds on the scorcher in the same manner as in the case of unconditioned dry mats and of dried wet mats.

The accompanying drawing illustrates my 50 special humidor, for use in my improved method of preparing matrices from dry flong mats. Figure 1 is a vertical longitudi-

nal section of my humidor, taken substantially on the line 1-1 of Fig. 2, the mat-holding frame being removed; Fig. 2 is a 55 section on the line 2-2 of Fig. 1, the mat-holding frame being in place and holding several mats. Fig. 3 is a section on the line 3-3 of Fig. 1, showing the mat-holding frame in place; Fig. 4 is an isometric view 60 showing the mat-holding frame; Fig. 5 is an isometric view of one of the moisteners of the humidor.

The humidor casing 10 has a cover 11 hinged at 12 and conveniently provided with 65 a hasp 13 whereby it may be fastened in closed position, the casing being substantially air-tight when the cover is closed. On the inner surfaces of the vertical wall of the casing 10 there are provided a number 70 of vertical guideways 14 opening at the top but partially closed at the bottom by a narrow shelf 15. The guideways 14 receive moisteners 16, conveniently in plate form, and made of some material, such as certain 75 kinds of clay, which absorbs water easily but allows it to evaporate readily therefrom. To prevent breakage, the moisteners are suitably bound at their edges in a metal binding 17. The moisteners 16, when in 80 place, are supported on the shelves 15, but project beyond the edges of such shelves so that they may be readily grasped and lifted out of the guideways 14.

A mat-holding frame 20 rests on the floor 85 21 of the casing 10 and is provided with a reticulated floor 22 spaced above the floor 21. Fastened to the upper surface of the floor 22 are a number of parallel, inverted U-shaped braces 23, conveniently of wire, 90 these braces being spaced from each other to receive the mats 24 to be conditioned. The braces 23 hold the mats 24 apart and in vertical position, so that the humid air within the humidor may circulate on all sides of 95 such mats and condition them uniformly.

In operation, a number of dry flong mats are placed in the spaces between the braces 23 within the casing 10, and the moisteners 16, first having been allowed to absorb a 100 sufficient quantity of water, are placed in the guideways 14. The cover 11 now being closed, the moisteners 16 yield up their moisture to the air within the casing 10,

which air circulates on all sides of every mat in the humidor and thoroughly conditions these mats by making them humid, but not wet, throughout. This humidifying of the mats is entirely uniform. The amount of moisture absorbed by a mat in humidifying is inconsiderable as compared with the amount of moisture in a wet mat. After having been allowed to remain in the humidor for several hours or longer, and it does not damage mats to remain in the humidor for much longer than that, the conditioned or humidified mats are removed from the humidor and molded in the usual manner under pressure on the exposed type face of the forms of type of which stereotype plates are desired. Then the matrices thus formed by the molding of the dry mats are placed for a few seconds on a scorcher, then being removed therefrom and used as molds for casting the stereotype plates desired. The scorcher may be of any suitable type, for there are several well-known and successful types. The scorching process consists of applying for a short time to the mats a sufficient degree of heat to drive off the small amount of moisture which is present in humidified dry mats conditioned by my process, as well as in wet mats after they have been dried in the drying table especially if exposed to the atmosphere during the time required for preparing them for casting, this degree of heat ordinarily being such that if applied continuously the mat will be charred or burned. Wet mats cannot be applied to the scorcher without preliminary drying, as they would be rendered useless by such application on account of the great amount of moisture they contain and on account of their laminated construction. One well-known type of scorcher consists merely of a metal plate, conveniently semi-cylindrical in shape, heated on the concave side by a gas flame, the mat to be scorched being placed on the convex surface for a few seconds, sufficiently long to drive out the moisture, but not sufficiently long to burn or char the mat. By having the mats properly conditioned, the type impression is rendered much clearer and sharper and of greater depth, as are also half-tones and other illustrations, than is the case when unconditioned dry mats are used, and the resultant stereotype plates and prints therefore are greatly improved. However, the amount of moisture absorbed in the conditioning process of the dry mats is so inconsiderable that it is not necessary to put them on a drying table, as is necessary with a wet mat, in order to avoid the possibility of disastrous effects from the presence of moisture when the stereotype plates are cast. Thus by my invention the time required for pro-

ducing a clear stereotype plate is very much reduced, especially when there is no drying 65 table in condition for use.

I claim as my invention:

1. That improvement in the art of preparing a matrix for stereotype plates, comprising the immersion of a dry mat in a 70 heavily humid gas for a sufficient time to produce the uniform humidification of the mat to such a degree of humidity as to render it pliant but still capable of scorching without preliminary drying; the formation 75 of type impression in such humidified mat; and scorching the matrix thus formed.

2. That improvement in the art of preparing a matrix for stereotype plates, comprising the immersion of a dry mat in a 80 heavily humid gas for a sufficient time to produce the uniform humidification of the mat to such a degree of humidity as to render it pliant but still capable of scorching without preliminary drying; and the formation 85 of type impression in such humidified mat.

3. That improvement in the art of producing stereotype plates, comprising the introduction of a dry mat into a humidor and 90 the maintenance in a heavily humid state of the air in such humidor and the consequent uniform humidification of such mat to a degree such that, after the formation of type impression therein, the matrix may be 95 immediately scorched; the withdrawal of such mat from the humidor and the formation of type impression therein; and the prompt scorching of the matrix.

4. That improvement in the art of producing stereotype plates, comprising the introduction of a dry mat into a humidor and the maintenance in a heavily humid state of the air in such humidor and the consequent uniform humidification of such mat to a 100 degree such that, after the formation of type impression therein, the matrix may be immediately scorched; the withdrawal of such mat from the humidor and the formation of type impression therein.

5. That improvement in the art of preparing a matrix for stereotype plates, comprising the immersion of a dry mat in a substantially vertical position in a heavily 115 humid gas for a sufficient time to produce the uniform humidification of the mat to such degree of humidity as to render it pliant but still capable of scorching without preliminary drying; and the formation of a type impression in such humidified mat. 120

6. That improvement in the art of preparing a matrix for stereotype plates, comprising the immersion of a dry mat in a position at an angle to the horizontal in a 125 heavily humid gas for a sufficient time to produce the uniform humidification of the

mat to such a degree of humidity as to render it pliant but still capable of scorching without preliminary drying; and the formation of a type impression in such humidified

5 mat.

In witness whereof, I, have hereunto set my hand at Indianapolis, Indiana, this

eighteenth day of February, A. D. one thousand nine hundred and thirteen.

JOHN FREMONT FREY.
